US00D861118S

(12) **United States Design Patent** (10) **Patent No.:** **US D861,118 S**
Burrow (45) **Date of Patent:** **** Sep. 24, 2019**

(54) **PRIMER INSERT**(71) Applicant: **TRUE VELOCITY IP HOLDINGS, LLC**, Garland, TX (US)(72) Inventor: **Lonnie Burrow**, Carrollton, TX (US)(73) Assignee: **TRUE VELOCITY IP HOLDINGS, LLC**, Garland, TX (US)(***) Term: **15 Years**(21) Appl. No.: **29/612,269**(22) Filed: **Jul. 31, 2017****Related U.S. Application Data**

(60) Continuation-in-part of application No. 14/748,508, filed on Jun. 24, 2015, which is a continuation of application No. 14/320,961, filed on Jul. 1, 2014, now Pat. No. 10,352,670, which is a continuation of application No. 14/011,202, filed on Aug. 27, 2013, now Pat. No. 9,546,849, which is a division of application No. 13/292,843, filed on Nov. 9, 2011, now Pat. No. 8,561,543.

CLAIM

The ornamental design for a primer insert, as shown and described.

DESCRIPTION

FIG. 1 is an isometric view of a primer insert showing my new design.

FIG. 2 is a front view of a primer insert showing my new design.

FIG. 3 is a side view of a primer insert showing my new design.

FIG. 4 is a top view of a primer insert showing my new design.

FIG. 5 is a bottom view of a primer insert showing my new design.

FIG. 6 is a cross sectional view of a primer insert showing my new design; and,

FIG. 7 is an isometric cross sectional view showing the primer insert molded into a cartridge casing.
